DESIGN FOR A FOUNTAIN PEN OR SIMILAR ARTICLE

John Hill, Hillside, N. J., assignor to Celluloid Corporation, a corporation of New Jersey

Application November 21, 1936, Serial No. 66,080

Term of patent 7 years

To all whom it may concern:

Be it known that I, John Hill, a subject of the King of England, residing at Hillside, county of Union, State of New Jersey, have invented a new, original, and ornamental Design for a Fountain Pen or Similar Article, of which the following is a specification, reference being had to the accompanying drawing, forming part thereof.

In the accompanying drawing:

The figure is a plan view of a fountain pen showing my new design.

The ornamentation of the fountain pen shown in the drawing comprises elongated diamond

shaped light colored areas presenting differential pearl luster effects disposed around the pen, the areas between these diamond shaped areas being of a plain contrasting color. The diamond shaped areas are substantially vertical and more or less parallel to each other and are so arranged around the pen that they give a spiral effect.

I claim:

The ornamental design for a fountain pen or similar article substantially as shown and described.

JOHN HILL.
